UNITED STATES PATENT OFFICE.

JOHN W. GARWOOD, OF LAWTON, OKLAHOMA.

BALING-PRESS.

1,270,145.

Specification of Letters Patent. Patented June 18, 1918.

Application filed August 1, 1917. Serial No. 183,926.

To all whom it may concern:

Be it known that I, JOHN W. GARWOOD, a citizen of the United States, residing at Lawton, in the county of Comanche and

5 State of Oklahoma, have invented new and useful Improvements in Baling-Presses, of which the following is a specification.

This invention relates to baling presses and particularly to that class of presses 10 which are equipped with mechanism for condensing the charge before the same is projected into the baling chamber for final compression.

The principal object of the invention is 15 to produce a condensing device of simple and improved construction which is adapted to be applied to and used in connection with a baling press of ordinary or conventional construction.

20 A further object of the invention is to simplify and improve the construction and arrangement of the condensing chamber.

A further object of the invention is to 25 simplify and improve the construction, arrangement and operation of the so-called condenser apron which constitutes one of the walls of the condensing chamber and which serves to compress or condense the charge within the chamber.

30 A further object of the invention is to simplify and improve the arrangement and operation of the plunger whereby the condensing charge is projected within the baling chamber in advance of the main plunger head 26.

35 With these and other ends in view which will readily appear as the nature of the invention is better understood, the same consists in the improved construction and 40 novel arrangement and combination of parts which will be hereinafter fully described and particularly pointed out in the claims.

In the accompanying drawings has been 45 illustrated a simple and preferred form of the invention, it being, however, understood that no limitation is necessarily made to the precise structural details therein exhibited, but that changes, alterations and modifications within the scope of the claims may be 50 resorted to when desired.

In the drawings:

Figure 1 is a side elevation of a baling press constructed in accordance with the invention.

55 Fig. 2 is a top plan view of the same.

Fig. 3 is a side elevation of the press seen

from the opposite side to that shown in Fig. 1 and showing in dotted lines the main plunger head at or near the end of the re-tracting stroke.

60

Fig. 4 is a view similar to Fig. 3 but showing in dotted lines the main plunger head at or near the end of the compression stroke.

Fig. 5 is a sectional detail view taken on 65 the line 5—5 in Fig. 1.

Fig. 6 is a sectional detail view taken on the line 6—6 in Fig. 1.

Corresponding parts in the several figures of the drawings are denoted by like 70 characters of reference.

The improved baling press may be mounted on ground wheels a portion of one of which is shown at 15 in Fig. 1 for convenience in transportation. The main press 75

box or press chamber is constructed with angle irons 17 at the corners thereof. 18 designates the tension screw and 19 the dogs or catches which are provided to prevent return of the compressed material. The side 80 walls 20 of the condenser chamber are substantially sector-shaped as will be clearly seen in Figs. 5 and 6, said side walls extending across the top of the press box, being curved downwardly and outwardly at one 85 side of the box. The condenser chamber

has a stationary end wall 21, the other end wall being formed by a plate or apron 22 which is mounted upon and carried by arms or levers 23 which are fulcrumed adjacent 90 to the bottom of the press box. The arms or levers 23 are offset as seen at 24 to accommodate the operating shaft 25. The main plunger head 26 which operates longitudinally in the press box is connected by a rod 95 or pitman 27 with a wrist pin 28 on the main driving wheel 29 which is supported for rotation and which may be driven in any convenient well known manner by power derived from any convenient source. 100

The stroke of the main plunger head should obviously be sufficient to carry material past the dogs 19 on the compression stroke and to carry the plunger from beneath the condenser chamber on the return or retracting 105 stroke.

Guided for reciprocation vertically in the condenser chamber, adjacent to the side wall 21, is a plunger 30 having adjacent to the open side of the condenser chamber a vertically disposed upwardly extending shield or guard 31. A rock shaft 32 which is sup-

110

- ported for rotation adjacent to the upper edge of the end wall 21 has a radially extending arm or lever 33 which is connected with the plunger 30 by a link 34, whereby 5 the plunger 30 may be moved vertically through the condenser chamber. The parts, including the means for actuating the rock shaft 32 to be hereinafter described, are to be so arranged and proportioned that when 10 the plunger is at the downward limit of its movement the pivot member 35, connecting the lever 33 with the link 34, will pass slightly beyond the center of the line of thrust, thereby locking the plunger 30 temporarily in a "down" position. The side walls 20 of the condenser chamber may be vertically grooved as seen at 36 to provide guide ways for guide members 37 on the plunger 30.
- 15 The actuating mechanism for the plunger 30 includes a quadrant or bell crank B fulcrumed at 38 and having a downwardly extending arm 39 with which two rods 40, 41 are pivotally connected. The rod 40 carries a cam head 42 lying in the path of a wrist pin 43 carried by a crank 44 on the shaft 45 which carries the main driving wheel 29. The rod 41 has a terminal hook 46 also lying in the path of the wrist pin 43 which latter, be it understood, may be equipped with an anti-friction roller 47. The rods 40, 41 are connected together by a coiled spring 48 tending to move the said rods in engagement with guide rollers 20 shown at 49, 50. A trip member 51 is provided for engaging a cam surface 52 on the hook member 46 for the purpose of disengaging said hook member from the wrist pin 43 at the proper time. The other arm 25 of the bell crank B is connected by a link 54 with an arm 55 extending radially from the shaft 32, the connections between the ends of the link 54 and the arms 53 and 55, respectively, being formed of universal joints 56 in order to enable the link to adapt itself to the movements of the arms 53 and 55 which operate in planes substantially at right angles to each other.
- 30 The pitman 27 which actuates the main plunger rod 26 is provided with an anti-friction roller 57. The rock shaft or fulcrum member 58 carries a bifurcated lever 59 having a relatively long curved arm 60 and a short arm 61 adapted to be actuated by the roller 57. Extending from the rock shaft or fulcrum member 58 angularly with respect to the lever 59 is an arm 61^a which is connected by a link 62 with an arm 63 that extends radially from the shaft 25, 35 the connections between the link 62 and the arms 61^a and 63, respectively, being formed by universal joints 64 whereby the link will adapt itself to the different planes in which the arms are adapted to swing.
- 40 The condenser apron 22 and the levers 23

carrying said apron are provided with convergent arms 65, 66 that combine to form driving brackets D, the apron being provided at each side thereof with a guide lug 67, said guide lugs operating in grooves or 70 guide ways 68 in the side walls 20 of the condenser chamber. The shaft 25 is provided with radial arms 69 which are connected by links 70 with the driving brackets D. It follows that when the rock shaft 25 75 is actuated, the condenser apron will be moved upwardly to condense the charge within the chamber or downwardly for the reception of a fresh charge according to the direction in which the rock shaft 25 is ac- 80 tuated.

An opening 71 for the admission of the division blocks between the bales is formed in one side wall of the condensing chamber just above the press box.

85

It is obvious that all the instrumentalities of the improved device are to be constructed, proportioned, and arranged in such a way as to operate in proper sequence and to cause the various steps of the operation 90 to be properly timed. The operation in a general way may be described as follows:

With the condenser apron at the downward limit of its movement, a charge of material is placed on the apron or within the 95 condenser. When the condenser apron is in this position, the plunger 30 will be locked at the lower limit of its movement, a charge of material having been projected within the baling chamber. When the main plunger head has traveled about one-third of the 100 reTRACTING stroke, the wrist pin 43 engages the cam head 42 of the push rod 40 whereby the bell crank B and related parts will be actuated to lift the plunger 30 to the upward 105 limit of its movement. When the main plunger head has traveled about two-thirds of the reTRACTING stroke, the roller 57 carried by the pitman 27 engages the long limb 60 of the bifurcated lever 59, causing the condenser apron to be moved in an upward direction, sweeping a charge before it beneath the raised plunger 30. The wrist pin 43 now engages the hook 46 of the baling rod 41 causing the bell crank B and related parts 110 to be actuated to move the plunger 30 in a downward direction, completely forcing the charge into the main baling chamber adjacent to the main plunger head 26 which is now practically at the end of the reTRACTING 115 stroke. As the main plunger head starts on the compression stroke, the roller 57 engages the short limb of the bifurcated lever 59, thus throwing the condenser apron open to receive another charge.

120 It will be seen that by the construction herein shown and described, a condenser of very large capacity is provided, this being to some extent due to the fact that the condenser apron is carried by arms or levers 125

125

130

- instead of being hinged at its bottom edge. Much greater space for the charge is thus provided, and very bulky material such as straw and the like may be successfully baled.
- 5 Owing to the large capacity of the condenser chamber, the same will also be easily filled or charged and the work may be done in a labor-saving manner. Each charge is forced completely down ahead of the main plunger, 10 thus making neat square-ended bales, and not leaving a "tag" from each feed to go in with the next, thus tying the flakes of the bale together. But little power will be required for operating the press, there being 15 expenditure of power for compression only and no loss from friction and binding, due to the charges being only partially forced down, as is the case with presses of the so-called "crane feed" type. Excessive strains 20 are eliminated for the same reason. The condenser stands open for nearly half the stroke or complete to and fro movement of the main plunger head, thus giving ample time for the placing of the charge, this being 25 a valuable improvement over other presses of the condenser type. The general construction is simple and inexpensive, and thoroughly practical and useful for the purpose for which it is intended.
- 30 Having thus described the invention, what is claimed as new is:
1. In a baling press, a press box, a condenser chamber having arcuate side walls extending across the press box and downwardly adjacent to one side thereof, levers fulcrumed adjacent to the bottom of the press box, an apron carried by said levers and operable between the side walls of the condenser chamber, and means for imparting to said apron an intermittent swinging movement, said apron having guide lugs and the side walls of the condenser chamber being provided with arcuate slots engaged by said lugs.
  - 45 2. In a baling press, a press box, a condenser chamber having arcuate side walls and a stationary end wall, levers fulcrumed adjacent to the bottom of the press box, an apron carried by said levers and operable between the side walls of the condenser chamber, driving brackets connected with the apron and the levers, a rock shaft supported adjacent to the press box, and having radial arms, links connecting said arms with the driving brackets, and means for actuating the rock shaft to produce a swinging movement of the levers carrying the condenser apron.
  - 55 3. In a baling press, a press box, a condenser chamber having arcuate side walls and a stationary end wall, levers fulcrumed adjacent to the bottom of the press box, an apron carried by said levers and operable between the side walls of the condenser chamber, driving brackets connected with
- the apron and the levers, lugs carried by the apron at the side edges thereof, a rock shaft supported adjacent to the press box, and having radial arms, links connecting said arms with the driving brackets, and 70 means for actuating the rock shaft to produce a swinging movement of the levers carrying the condenser apron, the side walls of the condenser chamber being provided with arcuate slots for the passage of the lugs 75 at the side edges of the apron.
4. In a baling press, a press box, a main plunger movable therein, a pitman actuating said plunger, a condenser chamber including side walls extending across the press box 80 and downwardly adjacent to one side thereof, levers fulcrumed adjacent to the bottom of the press box, an apron carried by the levers and operable between the side walls of the condenser chamber, driving brackets 85 connected with the levers and apron, means for actuating the apron carrying levers including a rock shaft and suitable connections, and means for actuating the rock shaft including a roller on the pitman of the main 90 plunger, a bifurcated lever having a long and a short arm disposed in the path of the roller, an arm connected with and extending angularly with respect to the bifurcated lever, an arm extending radially from the 95 rock shaft, and a link having universal connections with said arms.
5. In a baling press, a press box, a condenser chamber supported above and adjacent to one side thereof, a swingingly supported 100 apron operable in said chamber between the side walls thereof, a plunger supported for vertical movement in the condenser chamber, a rock shaft supported adjacent to the top of the condenser chamber, an arm extending 105 from said rock shaft, a link connecting the arm with the plunger, and means for so actuating the rock shaft that at the downward limit of the movement of the plunger, the pivot connection between the link and the 110 arm will be past the center of the line of thrust thereby locking the plunger at the downward limit of its movement.
6. In a baling press, a press box, a condenser chamber supported above and adjacent to one side thereof, a swingingly supported 115 apron operable in said chamber between the side walls thereof, a plunger supported for vertical movement in the condenser chamber, a rock shaft supported adjacent to the top of the condenser chamber, an arm extending from said rock shaft, a link connecting the arm with the plunger, and means for so actuating the rock shaft 120 that at the downward limit of the movement of the plunger, the pivot connection between the link and the arm will be past the center of the line of thrust thereby locking the plunger at the downward limit of its movement; the means actuating the rock 125 shaft
- 65 130

- shaft including an arm extending radially therefrom, a bell crank, a link having universal connections with one arm of the bell crank and with the arm extending from the 5 rock shaft, rods pivotally connected with the other arm of the bell crank, one of said rods having a terminal cam head and the other rod having a terminal hook, a spring connecting said rods together, guide members 10 in the direction of which the rods will be forced by the spring, and a crank having a wrist pin alternately engaging the cam head of one rod and the hook member of the other rod.
- 15 7. In a baling press, a press box, a condenser chamber supported above and adjacent to one side thereof, a swingingly supported apron operable in said chamber between the side walls thereof, a plunger supported for vertical movement in the condenser chamber, a rock shaft supported adjacent to the top of the condenser chamber, an arm extending from said rock shaft, a link connecting the arm with the plunger, and 20 means for so actuating the rock shaft that 25

at the downward limit of the movement of the plunger, the pivot connection between the link and the arm will be past the center of the line of thrust thereby locking the plunger at the downward limit of its movement; the means actuating the rock shaft including an arm extending radially therefrom, a bell crank, a link having universal connections with one arm of the bell crank and with the arm extending from the rock 30 shaft, rods pivotally connected with the other arm of the bell crank, one of said rods having a terminal cam head and the other rod having a terminal hook, a spring connecting said rods together, guide members 35 in the direction of which the rods will be forced by the spring, a crank having a wrist pin alternately engaging the cam head of one rod and the hook member of the other rod, and trip means for throwing the rod 40 having the terminal hook out of engagement with the wrist pin of the crank.

In testimony whereof I affix my signature.

JOHN W. GARWOOD.
